UNITED STATES PATENT OFFICE.

WILLIAM G. POWELL, OF ALTOONA, PENNSYLVANIA.

SIDE DOOR.

Application filed July 12, 1924. Serial No. 725,653.

This invention relates to side doors and which parts and members will be described more particularly to fabricated metal, side more fully in detail. doors for use on box cars.

It is a general object of this invention to provide an improved, metal, box car door.

It is another object of this invention to provide an improved fabricated metal box car door, the body of which is formed of flat plates reinforced at their meeting edges by offset flanges.

A further object of this invention consists in the provision of box car doors fabricated from several flat sheets of metal having offset flanges at their meeting edges and being provided with vertical edge stiffeners riveted to the sheets of the door in two planes at right angles to each other.

For a complete understanding of this invention, reference should be had to the following specification taken together with the accompanying drawings wherein:

Figure 1 is a partial elevation of the side of a box car showing the improved type of door according to this invention in position;

Figure 2 is a vertical section through the door and its supporting parts on line 2—2 of Figure 1, but shown on a much larger scale;

Figure 3 is a partial horizontal section of the forward meeting edge of the door and frame, taken on line 3—3 of Figure 1, but shown on an enlarged scale;

Figures 4 and 5 are partial horizontal sections on lines 4—4 and 5—5 respectively of Figure 1, shown on the same scale as Figure 3; and

Figure 6 is a partial vertical section on line 6—6 of Figure 1.

As clearly illustrated in Figure 1, a box car door constructed according to this invention is adapted to be applied to any conventional box car constructed of wood or steel. The car 10 shown in the figure is constructed of steel and is provided near its lower edge with the track 11 upon which rollers mounted on the door are adapted to travel, and with the bumpers or door stops 12 to limit the opening movement of the door.

The door 13 is constructed mainly of three pressed steel plates or panels 14, 15 and 16 riveted together along their horizontal meeting edges and reinforced along their vertical edges by means of the vertical stiffeners 17 and 18 securely riveted to flanges on the door plates. The upper edge of the plate 14 and the lower edge of the plate 16 are reinforced by horizontal stiffeners, all of

the main plates or panels 14, 15, and 16 of the door are offset outwardly at their meeting edges 19 and 20 as shown more clearly in Figure 2, where it will be noted that the plates are first bent upward nearly at right angles, forming the substantially horizontal portions 21, and then again bent nearly at right angles, forming the portions 22 parallel to the main portion of the panel. These portions 22 of adjacent panels are overlapped and securely riveted together, and each riveted seam together with the portions 21 adjacent thereto is in the nature of a large horizontal corrugation, adding materially to the stiffness of the door and resisting bending or buckling in the direction of the length of the panels. The lower edge 75

23 of the lower panel 16 is retained in its normal flat form and reinforced by the Z-bar 24 having its one flange 25 securely riveted to the inner face of the panel 16 with the lower face of the web in a line with the lower 80

edge of the panel and extending inwardly therefrom so that the lower flange 26 of the Z-bar forms in effect an inwardly offset guide flange for a purpose to be hereinafter described. The upper edge of the upper 85

plate 14 is adapted to be reinforced by the Z-bar 27 having its upper flange 28 securely riveted to the outer face of the flat portion of this panel. The upper edge of this panel together with its reinforcing Z-bar, serves 90

as will later be described to retain the door against falling away from the car, and in order that the upper edge may be stiffened

against bending about a horizontal axis, means are provided for attaching the opposite web 29 of the Z-bar to the panel. For this purpose, the material of the panel is pressed outwardly to form the short vertical corrugations 30, the summits of which are securely riveted to the flange 29, the material to form these corrugations being provided by allowing the upper edge of the panel to draw downwards, as shown at 31. By reference to Figure 6, this construction will be clearly understood.

The rear vertical edge of the door is reinforced by the distorted angle bar 32, a portion of one leg of which is bent inwardly to form an obtuse angle with the remainder. The end portions of the panels 14, 15, and 16 between their offset horizontal meeting edges are provided with right angled out-

wardly extending flanges 33 which are securely riveted to the leg 34 of the vertical stiffener 32. The leg 34 of this stiffener is of such a width that the front, right-angled 5 flange 35 of this angle rests upon the offset overlapping joints of the several panels, and at these points is securely riveted thereto by the rivets 36 as best shown in Figure 5.

The forward or leading edge of the panels 10 14, 15, and 16 is treated in exactly the same manner as just described in connection with the rear edge with the exception that the vertical stiffener member is a Z-bar instead of an angle, and has its web 36 riveted to 15 the right angled flange 33 at the end of the panels and its flange 38 riveted to the overlapped portions of the panels. The flange 39 of the Z-bar extends substantially in the same plane as the main part of the door, 20 as clearly shown in Figure 3 for a purpose to be later described. This method of constructing and fastening the vertical stiffeners of the main panels of the door results in an unusually rigid structure.

25 Riveting the vertical stiffeners to the panels by rivets arranged in two planes at right angles to each other eliminates any tendency for the vertical edge stiffeners to turn about a vertical axis, thus preventing 30 distortion or displacement of these members when the door is violently slammed either against the stops 12 when in open position or against the door posts, which will be later described, when in a closed 35 position.

As shown in Figure 1, the rollers 40 which are adapted to run upon the track 11 are mounted in castings which are securely riveted to the lower corners of the 40 panels 16, the upper flange of the lower stiffener 25 and the webs of the vertical edge stiffeners, thus serving not only as housings for the rollers but as ties for the horizontal and vertical edge stiffeners of the door. As 45 shown in Figure 2, the track 11 may conveniently be a channel member arranged with the web uppermost and supported from the longitudinal beams 42 of the car by means of the brackets 43. It is spaced a 50 slight distance from these beams 42 in order to provide a channel in which the lower flange 26 of the lower edge stiffener is adapted to run in order to guide the rollers and to prevent them from moving outwardly from the car and running off of the track. This flange 26 also serves in a measure as a weather strip closing the lower edge 55 of the door. While a bottom supported door has been disclosed it will be readily understood that the invention may be applied 60 equally as well to a top hung door.

The upper edge of the door is guided and prevented from lifting by means of the Z-bar 44 securely riveted to the upper structure of the bar and having the vertical

flange 45 which overhangs the vertical flange 28 of the upper horizontal stiffener of the door thus serving to shed water and to maintain the upper edge of the door against falling away from the car. At the same time 70 this Z-bar prevents any lifting of the door which might disengage the depending flange 26 from the channel between the track 11 and the beam 42, thereby insuring that the door always remains in position after the 75 Z-bar 44 has been riveted in place.

Reference to Figures 4 and 5 will disclose the manner in which the rear edge of the door is rendered water-tight and prevented from rattling when closed. In these figures, 80 to the outer metal side 46 of the car is shown bolted the door post 47 and having interposed between the siding and the post the web of the Z-bar 48 to which the door post is also secured by the bolts 49 in addition to those through the siding and having its outer flange 50 bent parallel to the web as shown at 51 in order to provide an edge 52 for the distorted leg of the angle member 34 on the edge of the door to press 85 against. The bent portion of this angle member being at an angle facing toward the direction of movement of the door will ride over the edge 52 and tend to draw the car door closer to the side of the car, thus 90 clamping the rearward edge of it against rattling and providing the overlapping joint which will keep out rain and wind no matter in which direction the car may be moving.

100 Figure 3 discloses in a similar manner a method of closing the forward edge of the door. In this case to the siding 46 of the car is bolted the door post 47 and has interposed between these two members the Z-bar 48 having a shortened outer flange 53 to which is riveted the one flange of a smaller Z-bar 54 having its outer flange 55 bent almost parallel to the web to provide a channel into which the flange 39 of the vertical stiffener 37 of the car door may fit to thus form a weather tight joint.

110 In order that the door may be securely locked in a closed position, there is provided the hasp 56 pivotally mounted upon the eye 57 having the flanges 58 and 59 riveted in two planes to the edge stiffener 37 of the car door. The offset bracket 60 mounted upon the side 46 of the car has integral therewith a stationary speed 61 over which the slot 62 in the hasp 56 is adapted 115 to be passed to retain the hasp in position. Suitable holes are provided for the insertion of the wires of the door seal.

120 From the foregoing description it will be seen that this invention contemplates the provision of the novel, all-metal, car door combining the characteristics of lightness, rigidity, ease of construction and cheapness. While but a single embodiment of this in- 125

vention has been illustrated, it will be apparent to those skilled in the art that numerous modifications may be devised without departing from the spirit of the invention as expressed in the following claims:

- 5 1. In a metal door, in combination, a plurality of connected panels, a flange on each meeting edge of each panel, offset from but substantially parallel to the plane thereof, flanges on adjoining panels being overlapped and secured together, a flange at the end of each panel substantially at right angles thereto and on the same side as said meeting flanges, and an angle bar edge stiffener secured to the ends of said panels by fastening one of its flanges to said right-angled end flange and its other flange to the ends of said offset flanges. 10
- 10 2. In a metal door, in combination, a plane sheet, spaced transverse corrugations therein, a flange at each end of said sheet at right angles to said corrugations and the plane of said sheet, an angle bar to stiffen each of said edges, said bar having one flange overlapping and secured only to the tops of said corrugations and the other to said end flange to thus form triangular trusses to prevent bending of the ends of said door about vertical axes. 15
- 15 3. In a metal door, in combination, a plurality of sheet metal panels and edge stiffeners, said panels being joined together at their meeting edges in a plane offset from the plane of the body of said panels, angled flanges on the vertical edges of said panels, angled vertical stiffeners fastened to said flanges and to the offset joints between said panels, an angled stiffener at the bottom of said door, short vertical corrugations spaced 20 along the upper edge of said door, and an angled stiffener having one flange fastened to the body of the upper panel and another flange fastened to the summits of said corrugations. 25
- 25 4. In a metal door of the sliding type, in combination a plurality of sheet metal panels each having a length equivalent to the width of the door, said panels having on their meeting edges, flanges offset from but parallel to the body of said panels, said flanges overlapping and being secured together so as to form transverse stiffening corrugations, angled flanges on the ends of said panels, edge stiffeners having flanges and a web, said web being joined to said angled flange and one of said flanges of said stiffeners being joined to said transverse stiffening corrugations, an angled stiffener joined to the bottom edge of said door and having an inwardly offset depending flange, the upper edge of said door being provided with a plurality of short vertical corrugations, an upper edge stiffener having two flanges, one joined to the summits of said corrugations and the other joined to the body of said upper panel. 30
- 30 5. In a metal door of the sliding type, in combination a plurality of sheet metal panels extending the width of the door and riveted together at their meeting edges, said riveted joints being offset outwardly from the bodies of said panels, right angled flanges on the ends of said panels, an angle having one leg riveted to one of said flanges, the other leg of said angle being riveted to said offset joints, a Z-bar having its web riveted to said other edge flange, one of the flanges thereof being riveted to said offset joints, a Z-bar riveted to the inside of the lower edge of said door with one flange depending, a Z-bar the upper flange thereof being riveted to the outside of the upper edge of said door, and a series of projections pressed outwardly from said edge and having their summits riveted to the other flange of said Z-bar. 35

In testimony whereof I hereunto affix my signature.

WILLIAM G. POWELL.
